In Great Britain March 10, 1950

13 Claims. (Cl. 317—88)

1

This invention concerns a new or improved electric lighter (for lighting, for example, cigars, pipes, cigarettes, fires, gas burners and the like) of the kind comprising a housing, and a torch normally located in said housing but adapted for withdrawal from the housing and automatic ignition on such withdrawal, said housing containing an induction coil, a battery or batteries, and spaced electric ignition contacts in circuit with said coil and battery or batteries, such contacts being arranged so as momentarily to be bridged by an electrically conducting part of said torch (as this is withdrawn from the said housing) and thereby momentarily to close the said battery circuit before again releasing the contacts and thereby breaking the said circuit to create a spark or sparks for effecting the ignition of a volatile liquid fuel, e. g. petrol, with which is impregnated or wetted a wick carried by and exposed at one end of the said torch.

The object of this invention is to provide a generally improved electric lighter of the kind referred to.

According to this invention there is provided an electric lighter of the kind referred to, wherein in the said housing comprises a base, a battery- and coil-carrying spider including a tubular body extending upwardly from said base and constituting a fuel reservoir at its lower portion and serving, at its upper portion, to receive the said torch when not in use; said body having externally a plurality of outwardly radiating ribs defining vertically disposed pockets arranged around the body for the reception of an induction coil and renewable batteries with their longitudinal axes substantially parallel to the axis of the said body; an outwardly directed flange at the upper end of said body bridging the upper ends of said pockets; electric contact means on said base and body-flange respectively for serially electrically interconnecting the coil and batteries placed in said pockets; a tubular socket above and coaxial with the upper portion of said body and containing the said spaced electric ignition contacts and also carrying means for connecting such contacts in series with said serially interconnected coil and batteries; and an outer closure shell for enclosing said coil and batteries, such shell being removable to give access to the open outer sides of said pockets to permit the batteries to be inspected or changed.

According to a further feature of the invention the upper portion of said body constitutes a cylinder in which is slidable the end of the torch at which the said wick is exposed, said torch be-

ing provided at this end with a collar constituting a piston freely slidable in said cylinder and serving, when the torch is withdrawn from the cylinder, to cause a flow of air into the latter for effecting the mixing of such air with the fuel vapour in the region of the wick of the torch and thereby to produce a more readily inflammable gaseous mixture in the cylinder and for drawing such mixture into the vicinity of the said ignition contacts.

According to a still further feature of the invention the bore of the lower part of the said tubular socket is of substantially the same diameter as the said cylinder and the socket is furnished with longitudinally extending radial ventilation grooves opening into the said socket bore and extending to the upper end of the socket and above and below the positions of the said ignition contacts, said ventilation grooves thus providing for an adequate supply of air to the vicinity of the said ignition contacts.

According to a still further feature of the invention the upper surface of the said socket is of funnel-like form to facilitate the pouring of the volatile fuel into the said fuel reservoir from the upper end of the said housing.

According to a still further feature of the invention the said shell is of inverted cup or bell shape and is adapted to screw on to the said base.

According to a further aspect of the invention there is provided an electric lighter of the kind referred to, wherein said housing comprises a battery- and coil-carrier having a tubular body and wherein electric contact means are provided for serially electrically interconnecting the induction coil and batteries of the latter and which the said carrier is adapted to bear; a tubular socket above and coaxial with the upper portion of the bore of the said carrier body and containing the said spaced electric ignition contacts and having ventilation grooves in the wall of its bore extending from the upper end of said socket to a position below the said ignition contacts, and the lower portion of said bore of the tubular battery and coil carrier serving as a fuel reservoir whilst the upper part of such bore constitutes a cylinder in which is freely slidable the operative end of the said torch which is provided, at or near this end, with a flange or collar constituting a piston freely slidable in said cylinder so that, when the torch is withdrawn from the cylinder, it serves to draw air into the cylinder for mixing such air with fuel vapour in the cylinder, thereby to produce a more readily inflammable gaseous mixture in the cylinder and for drawing such mixture into the vicinity of the said ignition contacts.

2

mable gaseous mixture in the cylinder in the region of the wick end of the torch, and to draw this gaseous mixture upwardly into the vicinity of the said ignition contacts.

Further features of this invention will become apparent from the appended claims and the following description wherein one embodiment of the invention is described with reference to the accompanying drawings, in which—

Figure 1 is a perspective view of an electric lighter constructed in accordance with this invention;

Figure 2 is a perspective view of the same electric lighter with its torch and outer closure shell removed;

Figure 3 is a perspective view similar to Figure 2 but with the component parts of the lighter shown separated to illustrate their construction and the method of assembling them, a portion of the torch being shown in the figure;

Figure 4 is an underneath plan of the socket part of the lighter and shows the ignition contacts;

Figure 5 is a vertical medial section of the lighter shown in Figure 1, the torch being removed;

Figure 6 is a section on line VI—VI, Figure 5;

Figure 7 is a view similar to that shown in Figure 5, but drawn to a larger scale and showing only the upper part of the lighter; and

Figure 8 is a diagrammatic view of the electric circuit of the lighter.

Referring to the drawings it will be seen that the lighter illustrated comprises a hollow housing, generally indicated by the reference 1, in which the operative parts of the lighter are located and which housing includes an outer bell-shaped shell 2 screwed at its lower end on to a circular base 3 which is externally screw-threaded at its upper part 4 and furnished with a knurling around its lower part 5 to enable a grip to be obtained on the base to assist relative rotation of the shell and base to connect them or disconnect them.

The lighter illustrated in the drawings is intended to be rested on a table, desk or the like and to prevent damage to the table or the like and also to prevent the slipping of the lighter thereon, the base of the lighter is conveniently provided with one or more rubber or like feet 6 mounted in recesses in lugs 7 on the base. A battery- and coil-carrying spider 8 is mounted centrally on the base 3 and includes a tubular body 9 extending coaxially upwardly from the base 3, the body 9 being provided with an annular rib 10 seating in a corresponding annular recess 11 (Figure 3) provided around a central hole 12 formed in the said base. The tubular body 9 is secured on the base 3 by means of a screw-threaded hollow plug 13 passing through the central hole 12 in the base and screwing into the interior of the lower end of the body 9, the plug 13 having a flange 14 seating in an annular recess 15 in the underside of the base 3. Not only does the plug 13 secure the spider 8 to the base 3 but it also seals the lower end of the tubular body 9.

The upper part of the tubular body 9 is of smaller internal diameter than the lower part thereof which constitutes a fuel reservoir 16. The upper part of the bore of the tubular body 9 constitutes a vertically disposed cylinder 17 which is adapted to receive the torch 18 of the lighter and to which further reference will subsequently be made. The cylinder 17 is conven-

iently defined by a dependent tubular part 19 coaxial with the tubular body 9 and conveniently formed integrally therewith as is clearly shown in Figure 5, for example.

An absorbent material, such as cotton wool, for example, is placed in the fuel reservoir 16 to bear the volatile inflammable liquid, e. g. petrol and an absorbent pad 20 which may be formed, for example, of asbestos, is located over the said absorbent filling for the reservoir and across the lower end of the cylinder 17 so that when the torch 18 is placed into the cylinder 17, as it normally will be when not in use, the lower end of the torch will rest on the pad 20 and the volatile liquid, with which the pad 20 is impregnated, will pass by capillary action to the exposed end of the wick 21 of the torch 18.

The torch 18 comprises a metal tube furnished at its upper end with a knob or equivalent handle 22 and is provided at its lower end with a collar 23 which is conveniently formed by an outwardly flared substantially frusto-conical part of the tube 18, the maximum external diameter of the collar 23 being only slightly less than the internal diameter of the cylinder 17 so that, during the withdrawal of the torch 18 from the lighter housing, the collar 23 will act in the cylinder 17 as a piston and tend to create a depression in the lower part of the cylinder 17 which will have the effect of drawing air down the cylinder 17 from the exterior of the lighter past the collar 23 into contact with the inflammable vapour below the collar whereafter continued withdrawal of the torch will have the effect of causing the piston-like collar 23 to draw the combustible mixture upwardly to the ignition contacts of the lighter, which will subsequently be described.

At its upper end the tubular body 9 is provided with a concentric outwardly directed flange 24 having a circular outline and having its undersurface parallel to the upper surface of the base 3, this flange conveniently being formed integrally with the body 9. Moreover, between the base 3 and the flange 24, the body 9 is provided externally with a plurality of outwardly radiating ribs 25 arranged equiangularly around the body and defining between them vertically disposed pockets 26 for the reception of an induction coil 27 and a plurality of renewable cylindrical batteries 28, the induction coil and the said batteries being arranged with their axes substantially parallel to the axis of the body 9. Conveniently the pockets 26 are of part-cylindrical form so that the spider 8 resembles a longitudinal fluted column.

A tubular socket, generally indicated by the reference 29, is arranged coaxially over the spider 8 and may conveniently be secured to the latter, although it could, if desired, be carried by the top of the shell 2. In the arrangement shown, the socket is fixed to the flange 24 of the spider 8 by screws 30.

The tubular socket 29 has an upper part 31 of approximately funnel form leading into a vertical central bore 32 having a diameter substantially the same as that of the cylinder 17 with which it is coaxial. It will be appreciated that the funnel-like form of the upper part 31 of the socket 29 facilitates filling of the reservoir 16 with fuel which can be poured into the reservoir via the socket and cylinder 17; thus the reservoir may readily be filled without the necessity for removing the plug 13. The tubular socket 29 is also provided with an annular flange 33 upon

which is placed a rubber or like sealing ring 34 adapted to be engaged by the upper end or top 35 of the shell 2, the latter being furnished with a central hole 36 to accommodate the upstanding rim 37 of tubular socket 29.

In the tubular socket 29 and around its bore 32 are provided a series of equiangularly-spaced, longitudinally extending, radial ventilation grooves 38 opening into the bore 32 and extending from the surface of the funnel-like part 31 of the socket downwardly to the bottom of the bore 32 where the grooves 38 merge wholly into this bore. Conveniently four such ventilation grooves are provided so that the vertical passage through the socket 29 formed by the bore 32 and ventilation grooves 38 is of cruciform shape at its upper end but, since the bases of the grooves 38 converge inwardly and downwardly, is of substantially circular form at its lower end.

As will be seen clearly from Figures 2, 3 and 4, for example, the tubular socket 29 has on its underside a bar-like portion 39 extending diametrically thereacross, this portion being hollow to accommodate electric ignition contacts 40 and 41 and further contacts 42 and 43 with which the ignition contacts co-operate. The hollow bar 39 also serves to receive a pair of diametrically opposed upstanding lugs 44 provided on the upper side of the flange 24 of the body 9 and serving to locate the socket with respect to the latter particularly during assembly of the lighter.

The ignition contacts 40 and 41 are conveniently each formed from a length of resilient metal wire bent to a serpentine or zig-zag form, each contact being arranged in a horizontal plane and anchored at its outer end upon the lower end of a vertical screw-threaded post 45 or 46 fixed to the socket 29 at its upper end. The inner ends of the ignition contacts project into the bore 32 of the socket 29, each entering this bore radially at diametrically opposed positions via one of the ventilation grooves 38 which is provided with a longitudinal slot 47 for this purpose, the said inner ends of the ignition contacts being located between the upper and lower ends of the bore 32 of the socket 29 as is clearly shown in Figures 5 and 7 for example. The inner ends of the ignition contacts 40 and 41 are also bent downwardly slightly and the minimum space between these contacts is less than the overall diameter of the collar 23 of the torch 18.

The said further contacts 42 and 43 are formed of resilient strip metal and are secured between their ends to the socket 29 by, but insulated from, the posts 45 and 46; the contacts 42 and 43 are also insulated from the ignition contacts 40 and 41. The inner ends of the contacts 42 and 43 are turned downwardly, as clearly shown in Figures 5 and 7, and these downturned portions are adapted to be engaged by the ignition contacts 40 and 41 respectively when the latter are deflected upwardly as a result of the withdrawal of the torch 18 from the cylinder 17, such upward deflection of the ignition contacts being effected by the collar 23 of the torch 18 engaging the inner downturned ends of the ignition contacts 40 and 41 and, as the torch is further withdrawn, causing the ignition contacts to be raised and engaged with the contacts 42 and 43 prior to the inner ends of the ignition contacts being released from the collar 23 and permitted to return to their original positions.

The outer end portions of the said further contacts 42 and 43 are extended outwardly from

the points of anchorage of these contacts to the socket and pass upwardly through slots 48 in the ends of the bar-like portion 39 of the socket so as to provide terminals 49 and 50 to which can be connected leads from the coil 27 and batteries 28 which are connected serially as shown in Figure 8.

The coil 27 is more permanently located in its pocket 26 of the spider 8 than are the batteries 28 since clearly it will not be necessary to remove the coil from the spider. It will be seen that the coil 27 is furnished with a soft iron core 51 (made of a series of lengths of iron wire) which projects above and below the ends of the coil, and the flange 24 of the spider is eccentrically furnished with a hole 52 to receive the upper projecting portion of the core 51 whilst the base 3 of the housing is furnished with an eccentrically located recess 53 in which seats the lower end of the coil 27 and a further and concentric recess 54 for the lower end of the core 51 of the coil. Thus when the spider 8, the coil 27, and base 3 are assembled together and secured by the plug 13, the coil 27 cannot thereafter be removed without dismantling the spider from the base.

On the other hand the batteries 28 can be mounted in and removed from the spider 8 simply by sliding them radially into or out of the spider transversely of their longitudinal axes, as is indicated in Figure 3.

The batteries 28 are conveniently of the well-known single cell "dry" Leclanché type of about 1½ volts, having a small central stud 55 at their upper ends forming one terminal or pole 55 and their exposed metal bases 56 forming their other terminal or pole.

As will be seen from the circuit diagram of Figure 8, the batteries are arranged two on either side of the induction coil 27 and the adjacent batteries are arranged in inverted relationship and contact means are provided on the base 3 for connecting each pair of adjoining batteries in series whilst contact means are provided on the flange 24 for connecting the batteries on either side of the induction coil to the latter and for connecting the end two batteries of the series to the said terminals 49 and 50 respectively.

The said contact means on the base 3 of the lighter comprise elements 57 of approximately V or U-shape in plan formed of resilient metal and each having upwardly bowed end portions 58 and 59; the central portion 60 of each of these contact elements is clamped between the base 3 and a rib 25 of the spider 8 of the lighter, the base 3 being provided with a radial recess 61 and the corresponding rib 25 of the spider 8 being formed with a co-operating projection 62 for engaging the central portion 60 of the element 57 to clamp and lock the latter in position on the base with each of the end portions 58 and 59 of the element projecting approximately radially into the respective pockets on either side of the spider ribs by which the elements are clamped to the base.

Each end portion 58 and 59 of the contact elements 57 may be provided with a protuberance 63 for engagement with the corresponding terminal or pole of a battery; the extremities 64 of each element 57 are also preferably slightly upturned so that as the end portions of the contact elements are depressed on placing a battery into the spider 8, these end extremities of the element can slide freely on the surface of the base 3.

The contact members carried by the flange 24 of the spider 8 each comprise a bowed strip 65 of resilient metal located radially in one of the battery pockets of the spider so as to be capable of engaging the upper terminal or pole of a battery slidden radially into such pockets, the said strip 65 having its outer end portion bent so as to constitute a tongue which can be passed vertically through a slot 66 provided through the flange 24 near the periphery of the latter, and then horizontally inwardly on the upper surface of the flange 24 so that the latter part of the tongue forms a terminal 67 (see. Figure 3, for example) to which may be soldered a flexible electric lead. There are four of the contacts 65 and each of these may be provided with a protuberance, like the protuberance 63 on the contact elements 57, for engaging the corresponding battery terminals or poles.

The terminals 67 of the two contacts 65 engaging the terminals or poles of the outer or end batteries of the series are connected by flexible leads 68 and 69 (Figure 3) to the terminals 50 and 49 respectively of the contacts 42 and 43, whilst the terminals 67 of the other two contacts 65 are respectively connected to the two ends 70 and 71 of the coil 27.

It will be seen that the fuel reservoir is entirely located between the base 3 and the flange 24 of the spider 8 and that the coil and battery pockets are arranged in a ring around the reservoir. Thus a very compact arrangement is achieved. It will also be noted that very ready access to the batteries is available simply by unscrewing the shell 2 from the base 3 and lifting the shell from the base, thereby exposing all the batteries and enabling them readily to be withdrawn radially outwardly from the spider either for inspection or replacement, renewing of the batteries being very simply effected, merely by engaging the lower end of the battery with one of the end portions of a contact element 57 and then sliding the battery radially into its pocket 26 of the spider thereby completing the engagement of the battery with the element 57 and also effecting the engagement of the upper end of the battery with one of the contacts 65. Since the tubular socket 29 is readily detachable from the spider 8, the contacts 40, 41 and 42, 43 can easily be inspected and repaired or replaced if necessary.

In using the lighter it will be understood that the torch is normally in the position shown in Figure 1 when the exposed end of the torch wick is in engagement with the absorbent pad 20 and thereby absorbs fuel from the pad. On withdrawing the torch from the lighter housing for use, the movement of the collar 23 of the torch up the cylinder 17 effects the drawing of air into the cylinder as hereinbefore described and continued upward movement of the torch effects the upward deflection of the ignition contacts 40 and 41 and their engagement with the further contacts 42 and 43 and consequently the closing of the electric circuit including the coil 27 and batteries 28. The completion of the withdrawal of the torch releases the ignition contacts 40 and 41 and thus breaks the electric circuit and creates the spark or sparks across these contacts in the vicinity of the receding exposed end of the torch wick, which is consequently ignited.

The ignition of the torch wick is greatly facilitated by the flow of air into the bore 32 of the socket 29 and the contacts 40 and 41 via the

ventilation grooves 38, since the volume of air necessary to produce a satisfactory inflammable gaseous mixture is many times greater than the volume of fuel vapour normally present in the cylinder 17 and bore 32.

Furthermore, when the lighter is being used repeatedly, a volume of carbon dioxide and other products of combustion will be present in these parts and this incombustible mixture is swept out by the incoming air during withdrawal of the torch and the production of a readily inflammable mixture in the vicinity of the ignition contacts is ensured.

During withdrawal of the torch from the lighter, the collar end of the torch is accurately guided through the socket bore 32 substantially centrally between the ignition contacts 40 and 41 this guiding being achieved by the portions of the socket bore 32 lying between the ventilation grooves 38, the bore thus having virtually a multi-line contact with the collar 23 of the torch during this operation.

On re-inserting the torch into the lighter housing, the ignition contacts 40 and 41 are downwardly deflected but the electric circuit is not closed and no spark produced since the ignition contacts 40 and 41 are no longer in engagement with the contacts 42 and 43. Moreover should the torch be re-inserted into the housing while still alight or smouldering, the flame or burning will quickly and automatically be doused when the wick end of the torch has passed the ignition zone in the socket 29 owing to the absence of a supply of air to the exposed end of the wick as a result of the good sliding fit of the collar 23 of the torch in the cylinder 17. This dousing effect is also assisted by the provision of a peripheral flange 72 around the upper part of the torch and which passes, as the torch is replaced in the lighter housing, within the rim 37 of the socket 29 and thereby decreases the flow of air into the socket, and finally seats upon the surface of the funnel-like part 31 of the socket and substantially cuts off the admission of air to the bore 32 of the socket.

The shell 2, base 3, spider 8, plug 13 and tubular socket 29 are all conveniently formed as thermoset resin mouldings but they may be made of any other suitable electrically insulating material.

We claim:

1. An electric lighter comprising a housing including a tubular body and a tubular socket at the upper end of said body, the lower part of said body constituting a reservoir for volatile liquid fuel and the upper part thereof constituting a tube leading to said reservoir; a torch adapted to be inserted coaxially through said tubular socket and into said tube; an absorbent wick carried by said torch and adapted to be charged with fuel from the said reservoir when the torch is in the tube; ignition contacts in the said tubular socket and adapted to be connected to a source of electric current and adapted, on withdrawal of the torch from the tube, to be actuated by the torch first to make and then to break the electric circuit thereby to produce a spark and thereby ignite the said wick, the said tubular socket having its upper surface in the form of a wide mouthed funnel having the bore of which leads directly, without interruption, into said tube so that liquid fuel may be poured from said funnel through said tube into said reservoir whereby the reservoir may be readily replenished with fuel without dismantling the lighter.

2. An electric lighter according to claim 1

wherein said ignition contacts are carried by the said tubular socket and the latter is provided internally with a plurality of longitudinally extending radial ventilation grooves opening into the bore of the socket and extending from the upper funnel-like surface of the socket to below the said ignition contacts, thereby to provide for an adequate supply of air to the said contacts when the said ignition contacts are being operated.

3. An electric lighter according to claim 2, wherein said ventilation grooves progressively decrease in their radial dimensions from their upper to their lower ends, the lower ends of such grooves merging into the lower part of the bore of said socket.

4. An electric lighter according to claim 3, wherein said source of electric current comprises one or more dry batteries and an induction coil located within said housing.

5. An electric lighter according to claim 4, including a further contact for and located adjacent each of the said ignition contacts and with which the adjacent ignition contact is adapted to be engaged momentarily when the torch is withdrawn from the said tube, the said further contacts being connected in series with the said battery or batteries and the said induction coil, the said ignition contacts being electrically independent of the said battery and coil circuit.

6. An electric lighter according to claim 5, wherein each of the said ignition contacts comprises a resilient metal wire of serpentine form secured, at one end, to the said tubular socket, the other end projecting radially into the bore of the said socket.

7. An electric lighter according to claim 6, wherein the said tube formed by the upper part of the said tubular body constitutes a cylinder and a collar, carried by the said torch at the end thereof at which the wick is exposed, constitutes a piston freely slidable in the said cylinder, said piston serving, when the torch is withdrawn from said cylinder, to cause a flow of air into the latter for effecting the mixing of such air with the fuel vapour in the region of the wick of torch, thereby to produce a more readily inflammable gaseous mixture in the cylinder and for drawing such mixture into the vicinity of said ignition contacts.

8. An electric lighter according to claim 7, wherein said collar is electrically-conducting and serves to bridge said ignition contacts and subsequently to release the latter for creating a spark upon withdrawal of the said torch from said housing.

9. An electric lighter according to claim 8, wherein the said housing also includes a cover shell adapted to be placed over and secured to the said body, the said cover shell being of approximately bell-shaped form and having a central aperture at its upper end adapted to receive the upper end of the said tubular socket whilst leaving the funnel shaped upper end of the latter exposed so that the reservoir may be replenished with fuel without removing the said cover shell.

10. An electric lighter according to claim 9, wherein the said housing includes a base, the said tubular body projecting upwardly from such base; a plurality of outwardly radiating ribs carried externally by said body and defining around the latter vertically disposed pockets for the reception of the said induction coil and battery or batteries; an outwardly directed flange pro-

vided on the upper part of said body closing the upper ends of said pockets and strip metal contacts on said body and base for serially interconnecting said coil and battery or batteries, the 5 said strip metal contacts being adapted to receive between them one or more radially inserted dry batteries and said cover shell being removable in one piece from the said body to expose such battery or batteries for radial insertion or withdrawal.

10. An electric lighter comprising a housing including a base, a tubular body extending upwardly from said base, means for locating an induction coil and at least one battery around said body, a fuel reservoir constituted by the 15 lower portion of said body, a tubular socket carried by the upper portion of said body and having its bore coaxial therewith and leading thereinto, spaced electric ignition contacts carried by 20 said socket and projecting radially into the bore thereof, the bore of said socket being furnished with longitudinally extending radial ventilation grooves, and said socket being formed at its upper end with a downwardly convergent surface 25 adapted to constitute a funnel for facilitating the pouring of a volatile liquid fuel through the bore of said socket and into said reservoir, means for serially electrically interconnecting an induction coil and at least one battery when placed around said body, means for connecting said 30 ignition contacts in series with said coil and battery, and an outer cover shell for enclosing said coil and battery and removable to give access thereto; and a torch and a wick carried 35 thereby and exposed at one end of said torch, said wick being adapted to be wetted with a volatile liquid fuel contained in said reservoir when the lighter is in use; said torch being normally located in said housing but being adapted 40 for withdrawal therefrom through said socket; and an electrically-conducting part on said torch adapted, on withdrawal of the latter from said housing, first to bridge said ignition contacts to complete an electric circuit through said coil 45 and battery, and subsequently to release said contacts on continued withdrawal of said torch thereby to open said circuit and to produce a spark for effecting ignition of the fuel with which said wick is wetted.

50. An electric lighter comprising a housing; a tubular body extending upwardly from the base of such housing; a reservoir for liquid fuel in the lower part of such housing; a tube formed by said tubular body and leading directly to 55 said reservoir; a tubular socket at the upper end of said body; a pair of ignition contacts in said tubular socket and extending into the bore thereof; a plurality of longitudinally extending radial ventilation grooves provided in 60 said socket and opening into the bore thereof, said grooves extending from the upper surface of said socket to below said ignition contacts and decreasing in their radial dimensions from their upper to their lower ends; an induction coil and at least one dry battery located within 65 said housing; a further contact for, and located adjacent, each ignition contact, said further contacts being connected in series with said battery or batteries and said induction coil; a torch adapted to be inserted coaxially through said tubular socket and into said tube; an absorbent wick carried by said torch and adapted to be charged with fuel from the said reservoir when the torch is in the tube; and an electrically conducting collar on said torch and 70 75

11

adapted, on withdrawal of said torch, to contact said ignition contacts and move them to engage said further contacts, thereby to complete the electric circuit through the said battery or batteries, the said induction coil, the said further contacts, the said ignition contacts and the said collar, and said collar being adapted, on further withdrawal of said torch, to pass said ignition contacts thereby to break the circuit and cause a spark to pass between 10 the said ignition contacts and the said collar, thereby to ignite the said wick.

13. An electric lighter comprising a housing including a base; a tubular body extending upwardly from such base; a reservoir for volatile liquid fuel formed by the lower part of the said tubular body; a tube formed by the upper part of said tubular body and leading directly to said reservoir; a tubular socket at the upper end of said body and provided with an upper surface 20 in the form of a wide-mouthed funnel the bore of which leads directly, without interruption, into said tube so that liquid fuel may be poured, via the said funnel, directly into the said reservoir; a pair of ignition contacts in the said 25 tubular socket and extending into the bore thereof; a plurality of longitudinally extending radial ventilation grooves provided in the said socket and opening into the bore thereof, said grooves extending from the upper funnel-like 30 surface of the socket to below the said ignition contacts and decreasing in their radial dimensions from their upper to their lower ends; an induction coil and at least one dry battery located within said housing; a further contact for, 35

12

and located adjacent, each ignition contact, said further contacts being connected in series with said battery or batteries and said induction coil; a torch adapted to be inserted coaxially through said tubular socket and into said tube; an absorbent wick carried by said torch and adapted to be charged with fuel from the said reservoir when the torch is in the tube; and an electrically conducting collar on the said torch and adapted, on withdrawal of said torch, to contact said ignition contacts and move them to engage said further contacts, thereby to complete the electric circuit through the said battery or batteries, the said induction coil, the said further contacts, the said ignition contacts and the said collar, and said collar being adapted, on further withdrawal of the said torch, to pass said ignition contacts thereby to break the circuit and cause a spark to pass between the said ignition contacts and the said collar, thereby to ignite the said wick.

H. L. RINK.
R. FARRAN SPENCE.
